WINDOW REGULATOR

John H. Roethel, Detroit, Mich., assignor to
 Marvel Equipment Corporation, Detroit, Mich.,
 a corporation of Michigan

Application March 27, 1937, Serial No. 133,339
 Renewed November 15, 1939

11 Claims. (Cl. 268—126)

This invention relates to window regulators suitable for use generally in connection with windows designed to be raised and lowered, the invention being particularly although not exclusively adapted for application to various types of vehicles, especially motor vehicles.

An object of the invention is to provide an improved regulator mechanism for raising and lowering a window glass or transparent panel, which mechanism is relatively simple, compact and economical to manufacture and in which the operation of the window is improved and greater ease in actuating the mechanism manually is achieved.

A further object of the invention is to provide a window regulator having one or a plurality of swinging arms and in which the arm is connected to the lower edge of the window through the medium of an improved roller and guide or glass retainer structure of simple and economical construction effective to permit movement of the window with greater ease through the reduction in the friction between the relatively sliding parts.

A further object of the invention is to provide in a window control mechanism an improved metal retainer or guide rail structure adapted to be secured to the lower edge of the window glass or panel and comprising opposed members having yieldable longitudinal rail or guide portions engageable by a roller or rollers, as the case may be, carried by the swinging regulator arm or arms, the construction and operation being such that when upward or downward pressure is applied to the rail or guide portions upon raising or lowering the window the rail portions will relatively yield or flex under the pressure of the roller or rollers thereby permitting relatively smooth un retarded travel of the rollers along the guide rails and reducing the effort required to operate the window. Moreover, when the regulator arm or arms are at rest the yieldable portions of the guide rails, upon release of the pressure thereon, will spring back to normal position and yieldingly grip the roller or rollers thereby preventing chattering or rattling of the parts during operation of the vehicle.

Another object of the invention is to provide an expandable and contractible guide rail structure comprising opposed flexible or yieldable track members adapted to be embraced by and interlocked with spaced rollers carried by a window regulator arm, the track members being sufficiently yieldable to be held under compression between the rollers and hence capable of automatically compensating for manufacturing vari-

ations prevailing in large scale production while also capable of sufficient yield during operation of the regulator to prevent locking of the rollers. As a consequence the rollers will rotate freely during their travel along the tracks and slight resistance to their travel will be occasioned, thereby minimizing any tendency to shift the window transversely in its plane as has heretofore occurred on account of high friction set up between the interlocking parts of the regulator arm and channel on the lower edge of the window.

Other objects of this invention will appear in the following description and appended claims, reference being had to the accompanying drawings forming a part of this specification wherein like reference characters designate corresponding parts in the several views.

Fig. 1 is a side elevation partly broken away and taken from the inside of an automobile door, illustrating one embodiment of the invention applied thereto for raising and lowering the window glass.

Fig. 2 is an enlarged vertical section taken through lines 2—2 of Fig. 1 looking in the direction of the arrow.

Fig. 3 is an enlarged fragmentary side elevation showing the connection between the window regulator and the retainer or guide rail structure secured to the lower edge of the window.

Fig. 4 is a perspective view of one of the guide rail members.

Fig. 5 is a perspective view of a tubular compressible member which may be employed in connection with the flexible track members.

Fig. 6 is a fragmentary side view illustrating the method of installing the window with respect to the regulator.

Fig. 7 is a fragmentary section somewhat similar to Fig. 2 illustrating a second embodiment.

Before explaining in detail the present invention it is to be understood that the invention is not limited in its application to the details of construction and arrangement of parts illustrated in the accompanying drawings, since the invention is capable of other embodiments and of being practiced or carried out in various ways. Also it is to be understood that the phraseology or terminology employed herein is for the purpose of description and not of limitation, and it is not intended to limit the invention claimed herein beyond the requirements of the prior art.

In the drawings there are illustrated, by way of example, certain embodiments of the present invention as combined in a window regulator of the parallel arm type such as shown in my U. S.

Letters Patents No. 1,986,532, patented January 1, 1935, and No. 2,008,517, patented July 16, 1935. It will be understood that the invention in its broader aspects may be utilized in connection with other preferred types of double arm window regulators, also single arm window regulators, and that the window regulator mechanism of the present invention may be used not only in connection with motor vehicle bodies but various other types of structures, vehicular or otherwise.

In the drawings there is shown at 10 a conventional front door of an automobile body having a main window opening closed by means of a glass and other transparent panel 11. The forward and rear upright edges of the panel 11 may be guided into and out of the window well by guides 12 and 13 extending thereinto. The window well is formed below the window opening between the inner metal door panel 14 and the outer metal body panel 15.

Except as hereinafter described the parallel arm window regulator herein illustrated, by way of example, may be constructed substantially as shown and described in my above mentioned Patent No. 2,008,517. As shown it comprises a metal mounting plate 16 secured by screws 17 to the panel 14. Mounted on the mounting plate 16 is a gear 19 which may be punched from a metal blank to provide a central opening. The gear of course may be otherwise fabricated. Gear 19 is in the form of a sector having teeth 19a meshing with a driving pinion on handle shaft 18. Gear 19 is pivoted at 20 to rotate on the mounting plate 16. The regulator also comprises a pair of parallel swinging arms 21 and 22. The arm 21 is pivoted to swing on a stud or pivot 23 secured to the mounting plate 16 within the open area of gear 19. The arm or bar 22 is pivoted on the stud or pivot 20 upon which the gear 19 is pivoted, and this arm is fixed to the gear 19 not only at the pivot 20 but by a rivet 24. The outer ends of the parallel arms 21 and 22 carry a bar or member 25 which, by way of example, is substantially T-shaped in form, and the outer ends of the arms are pivoted to the bar 25 at points 26 and 27, the pivot 27 being located in the lower end of the extension 25a of the bar 25. The vertical spacing of the pivots 20 and 23 corresponds to the vertical spacing of the pivots 26 and 27 whereby the arms swing in parallel relation during operation of the regulator. It will be understood that the connecting bar 25 may be designed in different ways and need not necessarily take the form of a T-shaped or L-shaped bar.

The window regulator mechanism, such as above described, is slidably connected to the lower edge of the window panel 11 through the medium of a guide and roller structure. There is fastened to the lower edge of the window panel 11 what is herein termed for convenience a window panel retainer structure or guide rail structure designated generally by the number 28 (Fig. 2).

This retainer of guide rail structure preferably comprises a longitudinal metal channel 29, which may be felt lined, rigidly secured to the lower edge of the panel. Spot welded to the rear face of the channel 29 and depending therefrom is a rail structure herein shown for convenience as formed in two similar sections 30. Each guide rail section 30, as shown in Fig. 2, may comprise a strip formed of sheet metal, such as spring sheet steel, bent or folded upon itself

to provide vertical contiguous portions 30a and 30b. These portions at their lower edges are turned inwardly at right angles to provide horizontal track sections 30c and 30d. The track sections, as shown in Fig. 4, may be rolled longitudinally to provide curved reversely extending ribs 30e and 30f. The opposed track members 30c and 30d are preferably formed so as normally to extend parallel to each other and being spaced apart, and these members are sufficiently resilient or flexible so as to permit them to be compressed together to a greater or lesser extent and yieldable under compression at predetermined times. If desired, in order to increase the spring resistance of these members to compression forces, an elastic rubber cylinder or dowel 32 may be mounted within the cylindrical portion 31 formed by the arcuate ribs 30e and 30f.

As herein shown the guide carried by the channel 29 is formed in two longitudinally spaced similar sections 30, each constructed as above described. It may, however, be formed in one length and notched out to provide a space for assembly purposes correspondingly to space 50. Cooperating with each of the track sections 30 are a pair of opposed grooved rollers 33 and 34 spaced apart in a vertical direction. Each pair of rollers is mounted at an end of the horizontal bar 25. The upper roller 33 of each pair is revolvably mounted upon a stud 35 riveted to bar 25 and each lower roller 35 of each pair is revolvably mounted upon a stud 36 riveted to the bar 25. Thus the grooved rollers of each pair engage the curved rail portions 30e and 30f at opposite sides of the track, these portions fitting into the annular grooves of the rollers and hence provide an interlocking connection between the tracks and rollers preventing displacement or disengagement of the rollers during operation. The regulator may be assembled with the window panel 11 in the manner shown in Fig. 6. The regulator is cranked to its lowest position and the window is slid vertically upon the guides 12 and 13 to the bottom of the well causing one pair of rollers to pass vertically between the track sections 30 into the space 50 and the other pair of rollers to pass by the end of one of the track sections 30 until the rollers are lined up with the rails 30e and 30f. Thereupon the window regulator is cranked upwardly so as to propel the rollers upon the rails. In practice after assembly of the regulator a suitable stop is provided on the regulator for limiting downward movement of the window to a position such as shown in Fig. 1 whereby the rollers are prevented from running off the ends of the tracks.

In the embodiment illustrated in Fig. 7 the bar 25 carries at each end a single roller 37 revolvably mounted upon a stud riveted to the end of the bar 25. Each track section comprises a sheet metal or spring steel strip 38 bent upon itself to provide upper and lower horizontal track sections 41 and 39 respectively. The rolled metal strip 38 is spot welded to the back face of the channel 29. The track section 39 is rolled to provide an upstanding groove or arcuate rib 40 and the track section 41 is rolled to provide a corresponding downwardly extending curved or arcuate rib 42. The ribs 40 and 42 are opposed to each other and vertically spaced so as to provide rails engaging opposite sides of each grooved roller 37. These track sections are resilient and yieldable under compression forces so as to be sprung apart during operation and adapted to spring together when the window is at rest so

that either or both track sections will at all times yieldingly engage the roller under sufficient pressure to hold the parts against rattling or vibrational noises.

In the operation of the device shown in Fig. 2, it will be seen that when the arms 21 and 22 are swung down to lower the window downward forces will be applied by rollers 33 to the rail sections 30e thereby tending to compress the latter and yieldingly contract the parts 30e and 30f, also tending to drop the rollers 34 away from the rail sections 30f. The upper rollers will travel freely along the rails with practically no frictional resistance. When the arms 21 and 22 are swung upwards the compression forces will be applied by rollers 34 against the bottom rail sections 30f and the reverse of the above operation will take place. It will also be seen that the compressible rail sections will accommodate variations in the clearance spaces between the grooved rollers. These slight variations invariably occur in large scale production where tolerances are allowed and also where slight manufacturing inaccuracies occur. Therefore by virtue of this flexible track structure it is possible to fix the pivots of the rollers, but at the same time to secure a snug fit of the rails within the grooves of the rollers. This snug fit, however, is yieldable so as to prevent the rollers from becoming locked which in turn would prevent or impede the free rotation thereof as they move back and forth onto the track. Not only does this construction prevent locking of the rollers on the tracks but it permits an extremely smooth and easy operation of the regulator, avoiding the necessity of increasing the gear ratio as heretofore in order to give the necessary extra power to offset the friction, as heretofore, of tight fitting studs travelling in guideways. The easy relatively frictionless operation of the rollers along the trackways also prevents shifting the window in its plane in an endwise direction which results in undue pressure of one edge of the glass on one of the guides 12 or 13 which heretofore has made the window harder to raise and lower.

In the operation of the device shown in Fig. 7 the upward pressure of the roller 31 when the window is raised, as shown by the arrow, tends to spring the rail 42 upwards sufficiently to separate the roller from the lower rail 40 thereby permitting the roller to travel freely along the track. The opposite action takes place when the window regulator is lowered, the roller at this time pressing downwardly upon the rail 40 and springing it slightly away from the upper rail 42. When the window regulator is at rest the track sections will tend to spring together and yieldingly hold the roller so that no rattling will take place. A similar action occurs in connection with the device of Fig. 2, which action may be amplified, if desired, by using the resilient rubber core 32. The use of the part 32 is, however, optional. When the regulator is at rest, the expansion of the track sections 30c and 30d tend to clamp the rollers and hold them against rattling during operation of the vehicle. Due to the yield of the members 42 and 40 it will also be seen that these members will accommodate slight variations in the diameter of the rollers 31 and also in the location thereof with respect to the guideways, particularly in cases where the rollers and guideways do not exactly line up when the regulator is installed due to variations incident to manufacturing tolerances or inaccuracies. This same

advantage is apparent in the use of the embodiment of Figs. 1 to 6 inclusive.

I claim:

1. In a window control mechanism, the combination of a swinging regulator arm having a pair of vertically opposed rollers mounted thereon, and a guide member adapted to be secured to the lower edge of the window and comprising opposed relatively yieldable tracks held under compression between said rollers.
2. The combination with a window regulator comprising a member having a sliding connection with the lower edge of a window, a pair of parallel swinging arms pivotally connected to said member at points spaced one above the other, and means for swinging the arms, said connection comprising vertically opposed relatively yieldable track members on the window and longitudinally spaced pairs of opposed rollers embracing the track members and effective to hold the same under compression.
3. A window panel retainer structure comprising a metal strip adapted to be secured to the lower edge of the panel and a roller guide member carried by said strip including a pair of vertically opposed relatively yieldable track members, and a compressible element interposed between said members.
4. A window panel retainer structure adapted to be secured to the lower edge of the panel, comprising a longitudinally extending pair of substantially horizontal track members spaced apart to permit them to spring together or apart, said members being formed with longitudinal grooves facing each other, and a compressible element confined in said grooves.
5. The combination with a swinging regulator arm having roller means adjacent the outer end thereof, of a window panel retainer structure comprising a metal strip adapted to be secured to the lower edge of the panel and a roller guide member carried by said strip including a pair of vertically opposed relatively yieldable track members grooved to provide interlocking alternate engagement with said roller means when the window panel is raised and lowered and to provide simultaneous relatively tight engagement with said roller means when the panel is at rest.
6. The combination with a swinging regulator arm having roller means adjacent the outer end thereof, of a window panel retainer structure comprising a metal strip adapted to be secured to the lower edge of the panel and a roller guide member carried by said strip including a pair of vertically opposed relatively yieldable track members spaced for the reception therebetween of said roller means and alternately engaged by said roller means when the window panel is raised and lowered, both of said track members providing a relatively tight yieldable engagement with said roller means when the panel is at rest.
7. In a window control mechanism, the combination of a swinging regulator arm having a pair of upper and lower spaced rollers mounted thereon, and a guide member adapted to be secured to the lower edge of the window and comprising opposed relatively yieldable tracks embraced by said rollers and alternately engaged by the rollers when the window is raised and lowered.
8. In a window control mechanism, the combination of a swinging regulator arm having a pair of upper and lower spaced grooved rollers mounted thereon, and a guide member adapted to be secured to the lower edge of the window

and comprising vertically opposed relatively yieldable tracks embraced by said rollers and interlocked therewith, the upper roller engaging the upper track and the lower roller being free of the lower track when the window is lowered and vice versa.

9. In a window control mechanism, the combination of a swinging regulator arm having roller means mounted at its outer end, and a retainer structure adapted to be secured to the lower edge of a window panel and comprising opposed tracks embracing said roller means and interlocked therewith, each track being yieldable in a vertical direction relative to the other and said tracks adapted to yieldingly grip said roller means when said panel is at rest, said roller means engaging the upper track only when the window is raised and engaging the lower track only when the window is lowered.

10. In a window control mechanism including a swinging arm and means for swinging the arm, the combination of a member having a sliding connection with the lower edge of a window panel and adapted to be pivotally connected

to the outer end of said arm, said connection comprising vertically opposed track members and roller means cooperable with one track member only when the arm is swung to raise the window and with the other track member only when the arm is swung to lower the window, each track being yieldable in a vertical direction relative to the other and said tracks adapted to yieldingly grip said roller means when said panel is at rest.

11. In a window control mechanism including a swinging arm and means for swinging the arm, the combination therewith of a sliding connection between the outer end of said arm and the lower edge of a window panel, said connection comprising vertically opposed track members and roller means cooperable with one track member only when the arm is swung to raise the panel and with the other track member only when the arm is swung to lower the panel, each track being yieldable in a vertical direction relative to the other and said tracks adapted to yieldingly grip said roller means when said panel is at rest.

JOHN H. ROETHEL.
